UNITED STATES PATENT OFFICE.

ALFRED M. DEMUTH, OF CHICAGO, ILLINOIS, ASSIGNOR TO U. S. SLICING MACHINE COMPANY, OF LAPORTE, INDIANA, A CORPORATION OF INDIANA.

WORK-HOLDER FOR SLICING-MACHINES.

1,257,587.

Specification of Letters Patent. Patented Feb. 26, 1918.

Application filed May 2, 1917, Serial No. 165,821. Renewed November 27, 1917. Serial No. 204,275.

To all whom it may concern:

Be it known that I, ALFRED M. DEMUTH, a citizen of the United States, residing at Chicago, in the county of Cook and State of Illinois, have invented certain new and useful Improvements in Work-Holders for Slicing-Machines, of which the following is a specification.

This invention relates to improvements in work holders for slicing machines, and more particularly to devices adapted to hold the work or article so that it may be completely cut or sliced and which devices are more specifically known in the trade as "last slice device".

Heretofore considerable difficulty has been experienced with devices of this character, in that a series of pins or article engaging prongs have been employed which penetrate the article in a direction transverse to the cutting plane of the knife or cutter, with the result, that the pin or prongs are engaged by the cutter before the article is completely sliced, thereby rendering it impossible to completely cut up the article.

To overcome these difficulties and objections, and to provide an improved simple and efficient device of this character, by means of which the article may be securely held while being cut, and which device is also adapted to hold the article by the very tip or end, thereby rendering it possible to cut soft, as well as hot meat, is one of the objects of the present invention.

35 A further object is to provide an improved device of this character by means of which a plurality of articles of different sizes or diameters may be simultaneously cut.

40 A further object is to provide an improved clamping device of this character embodying an article engaging portion, and means for limiting the movement of the clamping device in one direction, whereby the article engaging portion will be protected.

45 To the attainment of these ends, and the accomplishment of other new and useful objects as will appear, the invention consists in the features of novelty in substantially the construction, combination and arrangement of the several parts hereinafter more fully described and claimed and shown in the accompanying drawings illustrating this invention, and in which.

55 Figure 1 is a front elevation of an improved device of this character constructed

in accordance with the principles of this invention;

Fig. 2 is a horizontal sectional view as taken on the line 2—2 of Fig. 1;

Fig. 3 is a vertical sectional view as taken on the line 3—3 of Fig. 1;

Fig. 4 is a view similar to Fig. 1 of a modified form of the invention;

Fig. 5 is a detail sectional view taken on the line 5—5, Fig. 1;

Fig. 6 is a detail sectional view taken on the line 6—6, Fig. 1;

Fig. 7 is a detail perspective view of a portion of the clamping member;

Fig. 8 is a detail sectional view taken on line 8—8, Fig. 4;

Fig. 9 is an enlarged detail sectional view taken on line 9—9, Fig. 2.

Referring more particularly to the drawings and in the present exemplification of this invention, the numeral 10 designates generally a supporting member which is provided with uprights 11 projecting thereabove. The uprights are provided with a series of teeth 12, and the support 10 comprises a main body portion and a section 13 removably secured thereto, in any desired or suitable manner, such as by means of fastening devices 14. The uprights 11 are preferably connected with the section 13, so that when the latter is removed or detached from the portion 10, the uprights will also be removed. The body 10 is provided with a series of apertures 15 which are adapted to receive prongs or projections upon the meat table of a slicing machine, so that this device may be applied as an attachment thereto. The support 10 is also provided with guides 16 which engage uprights 17 for holding the attachment in position and fastening devices 18 may be provided, if desired, for securing the parts against separation.

Projecting above the support are a series of prongs 19 which are preferably in the shape of pointed pins. These prongs comprise a body portion 20, the end 21 of which is deflected laterally with respect to the body portion, and the section 13 (see particularly Fig. 6) is provided with a transverse aperture 22 into which the deflected portion 21 of the prong 20 is adapted to be inserted and the extremity of the portion 21 is upset or secured to the section 13 in any desired or suitable manner. The section 13 is also pro-

vided with a recess 23 adjacent the front edge thereof and which recess communicates with the aperture 22 so that the body portion of the prong 20 will enter the recess. 5 By mounting the prongs in the section 13 in the manner described, it will be manifest that the prongs may be easily removed and in order to accomplish this all that is necessary is to remove the fastening devices 14, 10 which will allow the section 13 to be detached and the prong may then be readily removed. It will be noted that the extremity of the portion 21 of the prong stands adjacent the face of the section 13, which 15 abuts the section 10 so that when the parts are assembled that end of the prongs will be protected.

A clamping member 24 is provided in its extremities with openings 25 into which the 20 uprights 11 are adapted to project so that the clamping member may be moved upon the uprights toward and away from the support. The lower face of the clamping member 24 is provided with a series of teeth 26 that extend entirely across the face and 25 transversely thereof. These teeth are so arranged that they will incline in a direction toward one end of the member 24, and in a direction that they will be opposed to the 30 operation of the cutter 27. That is to say, when the clamping member rests upon the article and the machine is operated, the cutter when it engages the article has a tendency to shift the article laterally, but 35 owing to the inclination of the teeth 26, it will be seen that the teeth will embed themselves in the article, under such action of the cutter.

In the form of the invention shown in 40 Figs. 4 and 7, the clamping member is provided in one of its faces with upright recesses or grooves 28, so that when the clamping member is moved into the position shown in Fig. 4, so as to stand close to the 45 support, or to grip an article of a size that the prongs 19 will extend entirely through the article, the prongs will enter the recesses 28 to be protected thereby.

Any suitable means may be provided for 50 securing the clamping members in position, and to that end there may be provided a recess 29 in one of the faces of the clamping member extending lengthwise thereof. Arranged to move within this recess are elements 30, 31, which are preferably provided with beveled extremities 32 that respectively coöperate with the teeth 12 of the uprights 11. An operating handle 33 is connected as at 34 with the adjacent ends of the elements 30, 31, and is pivotally mounted as at 35 so that by manipulating the lever 33 the elements 30, 31 may be moved into a position to lock or unlock the clamping member. The elements 30, 31, may be each provided 65 with a slot 36 through which fastening bolts

37 pass, which act as a guide for the elements, and the fastening elements 37 may also serve as a means for securing the handle 38 to the clamping member 34. This handle 38 may be of any desired configuration but is secured to the clamping member between the extremities thereof and in a position that it will stand intermediate the uprights 11, so that in adjusting the clamping member it may be maintained in a horizontal position by the operator, who can manipulate it with one hand. 70 75

In the form of the invention shown in Figs. 1 and 5, the clamping member 24 is provided with a series of apertures 39 extending transversely therethrough and a plurality of pins or prongs 40 are also provided. These pins or prongs are laterally deflected as at 41 at one end thereof, and the deflected portions are inserted in the apertures 39 and secured in any suitable manner preferably by upsetting the extremity of the portion 41 as at 42. The clamping member is also provided with a series of recesses 43 in one face thereof, and which recesses 90 communicate with the apertures 39, so that when the pins 40 are in position with respect to the clamping member, a portion of the body of the pin will rest in the recess 43. 80 85

These pins 40 are of a considerable length 95 so as to impale articles of any desired size, and will also simultaneously impale and hold a plurality of articles of different sizes upon the support and the pins 40, together with the pins or prongs 21 are arranged in 100 a staggered relation as well as in the same vertical plane.

In operation, the article to be sliced is placed upon the holder by inserting the pins or prongs 19 in the extreme tip of the article and then lowering the clamping member 24, of the form shown in Fig. 1, so that the pins 40 will impale the article. The lever 33 is then adjusted to shift the elements 30 and 31 to lock the clamping member in 110 the desired position. 105

In the form of the invention shown in Fig. 4, where the pins 40 are omitted, the clamping member 24 is lowered so that the teeth 26 will engage the article, and the 115 teeth 26 will also engage the article when the form shown in Fig. 1 is used.

During the cutting operation, the teeth 26, being disposed in opposition to the cutter, will embed themselves in the article and the 120 article will be held securely.

In order to prevent or overcome the tendency of a rocking movement of the clamping member 24 upon the uprights 11, brackets 44 may be provided which are connected 125 with the clamping member and these brackets embrace the uprights 11. In order to arrest or limit the movement of the clamping member 24 toward the support, to protect the pins 40 and the teeth 26, the bracket 44 130

may be shaped with a laterally projecting shoulder 45 which is adapted to engage and rest upon the ends of the uprights 11. With this improved construction, it will be manifest that when the clamping member 24 is lowered, the portions 45 of the brackets 44 will engage the ends of the uprights and thereby arrest the movement of the clamping member.

10 It will also be manifest that with this improved construction, it is possible to use the same as an individual holder, that is to say, an article may be clamped or secured to the holder and allowed to remain in the 15 holder until it is completely cut up, and any number of these holders may be employed for different articles as may be desired, as they may be readily attached to or detached from the machine.

20 It will also be manifest that the prongs and pins are so arranged that they will be in a plane parallel to the cutting plane, thereby obviating any danger of the cutter contacting with the prongs, and also rendering it 25 possible to completely cut up the article.

It is also possible to cut a plurality of articles of different sizes or diameters simultaneously, that is to say, a plurality of articles of different size and diameter may 30 be secured to the holder at the same time inasmuch as the prongs are of such a size that they will penetrate all of the articles and thereby secure them to the holder. If desired the support 10 may be provided with 35 suitable handles 46 by means of which it may be lifted from the machine and transported.

The recesses or grooves 28 are so arranged in the face of the clamping member 24, that 40 when the pins 49 stand within the recesses, the ends of the teeth 26 will stand substantially flush with the outer faces of the pins, so that the teeth 26 will act upon the article between the pins 19, and being substantially 45 flush with the outer faces of the pins, the pins will be protected during the slicing operation. It will also be manifest that by providing the handle 38 intermediate the ends of the clamping member, it is not necessary to force the article down upon the pins 50 19 before the clamping member is lowered, that is to say, the article can be held in one hand just above the points of the pins 19 and then the clamping member can be lowered 55 with some force, which will act to drive the article down upon the pins. The handle 38 being arranged intermediate the ends of the clamping member, enables the operator to actuate the clamping member with one 60 hand, while his other hand is free to hold the article while the clamping member is being lowered.

While the preferred form of the invention has been herein shown and described, it is to 65 be understood that various changes may be

made in the details of construction, and in the combination and arrangement of the several parts, without departing from the spirit of this invention, and it is therefore desired that the drawings submitted above shall be 70 considered as being merely diagrammatic.

What is claimed as new is:

1. An article holder for slicing machines embodying a support for the article, article engaging means connected with the support, 75 an article clamping member coöperating with the support, and teeth extending across one face of the said member, said teeth projecting in a general direction toward one end of the member. 80

2. An article holder for slicing machines embodying a support for the article, an article clamping member coöperating with the support, an upright guide for the clamping member, and a stop device for limiting 85 the movement of the clamping member toward the support.

3. An article holder for slicing machines, embodying a support for the article, an article clamping member coöperating with 90 the support, an upright guide for the clamping member, and a stop device for limiting the movement of the clamping member toward the support, said stop device coöperating with the said guide. 95

4. An article holder for slicing machines, embodying an article support, an upright projecting thereabove, an article clamping member movable upon the upright toward and away from the support, and a stop device for limiting the movement of the clamping member, said stop device embodying means adapted to engage the end of the upright. 100

5. An article holder for slicing machines, 105 embodying an article support, an upright projecting thereabove, an article clamping member movable upon the upright toward and away from the support, and a bracket projecting from the clamping member, said 110 bracket embodying a laterally projecting shoulder adapted to engage the end of the upright to arrest the movement of the clamping member in one direction and for supporting the member. 115

6. An article holder for slicing machines, embodying an article support, an upright projecting thereabove, an article clamping member movable upon the upright toward and away from the support, a bracket projecting from the clamping member, said bracket embodying a laterally projecting shoulder adapted to engage the end of the upright to arrest the movement of the clamping member in one direction and for supporting the member, and a fastening device coöperating with the upright for securing the clamping member in its adjusted position. 120

7. An article holder for slicing machines, 125

embodying an article support, an upright projecting thereabove, an article clamping member movable upon the upright toward and away from the support, a stop device 5 for limiting the movement of the clamping member, said stop device embodying means adapted to engage the end of the upright, and a fastening device carried by the said member and coöperating with the upright 10 for securing the member in its adjusted position.

8. An article holder for slicing machines, embodying an article support, an upright projecting thereabove, an article clamping member movable upon the upright toward and away from the support, a bracket projecting from the clamping member, said bracket being shaped to embrace the upright, and a shoulder on the bracket, said 15 shoulder being adapted to engage the end of the upright to arrest the movement of the clamping member and to support the latter.

9. A work holder for slicing machines, embodying an article support, article holding means upon the support, a clamping member movable toward and away from the support, and article engaging teeth on one 25 face of the member, said teeth extending transversely thereof, and pins coöperating 30 with said teeth, said pins projecting from the clamping member and extending beyond the teeth for impaling the article.

10. A work holder for slicing machines, embodying an article support, article holding means upon the support, a clamping member movable toward and away from the support, and article engaging teeth on one 35 face of the member, said teeth extending transversely thereof, pins coöperating with 40 said teeth, said pins projecting from the clamping members and extending beyond the teeth for impaling the article, and means for securing the said member in clamping relation to the said support.

45 11. A work holder for slicing machines, embodying an article support, upwardly projecting article engaging pins, a clamping member movable toward and away from the support, downwardly projecting pins 50 connected with the member and coöperating with the first recited pins, and article engaging teeth arranged on the clamping member and coöperating with the pins.

12. A work holder for slicing machines, embodying an article support, upwardly projecting article engaging pins, a clamping member movable toward and away from the support, downwardly projecting pins 55 connected with the member and coöperating 60 with the first recited pins, article engaging teeth arranged on the clamping member and coöperating with the pins, and means connected with the clamping member for arresting the movement of the member and 65 second recited pins toward the said support.

13. A work holder for slicing machines, embodying an article support, article engaging means projecting thereabove and embodying upstanding impalement pins, a clamping member movable toward and away from the support, impalement pins 70 depending from the member, and means for securing the clamping member in its adjusted position, all of said pins operating in the same vertical plane. 75

14. A work holder for slicing machines, embodying an article support, article engaging means projecting thereabove and embodying upstanding impalement pins, a clamping member movable toward and away from the support, impalement pins 80 depending from the member, and means for securing the clamping member in its adjusted position, all of said pins operating in the same vertical plane, the pins on the support 85 and clamping member being arranged in staggered relation.

15. A work holder for slicing machines, embodying an article support, article engaging means projecting thereabove and embodying upstanding impalement pins, a clamping member movable toward and away from the support, impalement pins 90 depending from the member, means for securing the clamping member in its adjusted position, all of said pins operating in the same vertical plane, and article engaging teeth 95 on the lower face of the clamping member, said teeth and pins coöperating to hold the article. 100

16. A work holder for slicing machines, embodying an article support, uprights projecting thereabove, a clamping member movable upon the uprights, and means carried by the said member and coöperating with the uprights for securing the clamping member in its adjusted position, the said means embodying oppositely disposed sliding elements adapted to engage the respective uprights, and an operating handle common to 110 and connected with the inner ends of said elements for operating them. 115

17. A work holder for slicing machines embodying an article support, uprights projecting thereabove, a clamping member movable upon the uprights, locking elements recessed into the said member, one end of each of said elements being disposed in proximity to each of the uprights, and an operating element, common to and connected with the other ends of the said element for simultaneously actuating them, said elements coöperating with the uprights to lock the clamping member in position. 120

18. A work holder for slicing machines, embodying a body portion, there being an aperture extending transversely there-through, and an impalement pin, one end of the pin being deflected laterally with respect to the body of the pin, the deflected 125 130

end of the pin being seated in the said aperture.

19. A work holder for slicing machines, embodying a body portion, there being 5 an aperture extending transversely there-through, and an impalement pin, one end of the pin being deflected laterally with respect to the body of the pin, the deflected end of the pin being seated in the said aperture, said body being also provided with a recess in one face thereof, said recess being disposed adjacent to and having communication with the aperture and into which recess, a portion of the pin is seated.

15 20. A work holder for slicing machines, embodying a support, article engaging pins projecting thereabove, uprights projecting thereabove, a clamping member movable upon the uprights toward and away from 20 said support, and teeth on the lower face of the member extending transversely thereof, said teeth projecting in a direction toward one end of the member, there being recesses in the clamping member to receive 25 the said pins.

21. A work holder for slicing machines, embodying a support, article engaging pins projecting thereabove, uprights projecting thereabove, a clamping member movable 30 upon the uprights toward and away from said support, teeth on the lower face of the member extending transversely thereof, said teeth projecting in a direction toward one 35 end of the member, there being recesses in the clamping member to receive the said pins, and a handle connected with the clamping member and disposed intermediate the ends of the member.

22. An article holder for slicing machines 40 embodying a support for the article, article engaging means connected with the support, an article clamping member co-operating with the support, teeth extending across one face of the said member, said 45 teeth projecting in a general direction toward one end of the member, and a handle connected with the said member and disposed intermediate the ends of the member.

23. A work holder for slicing machines, 50 embodying an article support, said support embodying separate sections, impalement pins connected with one of the sections, one end of the pins being seated in one of the sections, the extremities of said ends being disposed adjacent that edge of the said section which stands adjacent the other of the sections, and means for detachably securing 55 the sections together.

24. A work holder for slicing machines, 60 embodying an article support, said support embodying separate sections, impalement pins connected with one of the sections, one end of the pins being seated in one of the sections, the extremities of said ends being 65 disposed adjacent that edge of the said sec-

tion which stands adjacent the other of the sections, means for detachably securing the sections together, and an upright connected to and extending above that section to which the said pins are connected.

70 25. A work holder for slicing machines, embodying a work support, a clamping member co-operating with and movable toward and away from the support, and a series of coplanar spaced, oppositely disposed 75 work impalement pins connected with the support and the clamping member.

26. A work holder for slicing machines, embodying a work support, a clamping member co-operating with and movable toward and away from the support, a series of coplanar, spaced, oppositely disposed work impalement pins connected with the support and clamping member, and teeth on the lower face of the clamping member, 80 said teeth extending transversely there-across, and co-operating with the pins on the member to hold the work.

27. A work holder for slicing machines, embodying a work support, a clamping 90 member co-operating with and movable toward and away from the support, a series of coplanar, spaced, oppositely disposed work impalement pins connected with the support and the clamping member, teeth on 95 the lower face of the clamping member, said teeth extending transversely thereacross and co-operating with the pins on the member to hold the work, and a handle connected with the clamping member intermediate the 100 ends thereof for actuating the member.

28. A work holder for slicing machines, embodying a work support, a clamping member co-operating with and movable toward and away from the support, a series 105 of coplanar, spaced, oppositely disposed work impalement pins connected with the support and the clamping member, uprights upon which the clamping member is adapted to move, and a fastening device carried with 110 the clamping member and co-operating with the uprights for securing the clamping member in adjusted position.

29. A work holder for slicing machines embodying an article support, spaced prongs 115 projecting thereabove, a clamping member, and teeth extending transversely of the article engaging face of the member, said member having vertical recesses adapted to receive the said pins, whereby the said teeth 120 will stand substantially flush with the outer face of the pins when the pins project into the said recesses.

30. A work holder for slicing machines, embodying an article support, spaced prongs 125 projecting thereabove, and a clamping member, said member having an undulated article engaging surface and upright recesses adapted to receive the pins, whereby the undulated surface will engage the article be- 130

tween the pins and the said undulated surface will stand substantially flush with the outer surface of the pins when the pins extend into the recesses.

5 31. A work holder for slicing machines, embodying an article holder, a clamping member, means for guiding the clamping member into and out of operating position, teeth extending across the article engaging

10 surface of the clamping member, and prongs projecting from said member and extending beyond the said teeth, the outer surface of the prongs being disposed in a plane substantially flush with the lateral ends of said teeth.

15 32. A work holder for slicing machines, embodying an article holder, a clamping member, a guide for directing the clamping member into and out of operating position, and a stop device connected with the clamping member and adapted to engage the end of the said guide for limiting the movement of the clamping member in one direction.

20 33. As an article of manufacture, an article clamping member for slicing machines, said member having teeth extending across the article engaging face thereof, the said teeth projecting in a general direction toward one end of the member.

25 34. An article holder for slicing machines, embodying an article support, teeth projecting above the support, the outer face of the teeth being substantially flush with the edge of the support, and an article clamping member coöperating with the teeth and support.

30 35. An article holding member for slicing machines, embodying a body portion and downwardly extending pointed tines or pins projecting from said body, the outer face of the tines or pins being substantially flush with the front edge of the said body portion.

35 36. An article holder for slicing machines embodying an article support, and an article clamping member coöperating with the support, said clamping member having means substantially flush with its edge adapted to simultaneously secure and hold a plurality of articles of different diameters resting upon 50 the support.

37. An article holder for slicing machines, embodying an article support, an article holding member coöperating with the support having an edge adjacent which the cutting is done, and a plurality of extended impalement pins depending from the said member, the outer face of said pins being substantially flush with said edge, said pins being spaced from each other in a direction lengthwise of the said member, whereby a 60 plurality of articles of different diameters resting upon the support may be simultaneously held by said member.

38. An article support having an edge adjacent which the cutting is done, and a 65 clamping member coöperating with the support, said member having extended pointed pins or tines depending therefrom, the outer face of said pins or tines being substantially flush with the said edge of the support. 70

39. An article holder for slicing machines, said holder embodying an article support, spaced uprights projecting thereabove, a clamping member coöperating with the support, a handle connected with the member 75 intermediate its ends, and extended bearings on the members having engagement with the uprights for holding the clamping member for free and unbinding sliding movement upon the uprights and for alining said member with the cutting edge of the support.

40. A work holder for slicing machines embodying an article support, said support embodying separate sections, impalement pins connected with one of the sections, one 85 end of the pins being seated in one of the sections, the extremities of said ends being disposed adjacent that edge of the said section which stands adjacent the other of the sections, and means for detachably securing 90 the sections together.

In testimony whereof I have signed my name to this specification, in the presence of two subscribing witnesses, on this 28th day of April, A. D. 1917.

ALFRED M. DEMUTH.
